UNITED STATES PATENT OFFICE.

JOHN G. ILS, OF SAN FRANCISCO, CALIFORNIA.

DESIGN FOR A PORTABLE FURNACE.

SPECIFICATION forming part of Design No. 26,999, dated April 27, 1897.

Application filed March 11, 1897. Serial No. 627,062. Term of patent 7 years.

To all whom it may concern:

Be it known that I, JOHN G. ILS, a citizen of the United States, residing in the city and county of San Francisco, and State of California, have invented a new and useful Design

5 for Portable Assay-Furnaces, of which the following is a specification, reference being had to the accompanying drawings, forming a part hereof.

10 Figure 1 is a perspective view of a portable assay-furnace, showing my new design. Fig. 2 is a top view of the furnace. Fig. 3 is a sectional view taken horizontally through the furnace above the grate-surface, these views being considered necessary to fully illustrate 15 my design.

The leading features of my design comprise a rounded body in cross-section, somewhat resembling in outline a horseshoe, with the 20 semicircular portion to the rear; a flat front with openings covered by hinged doors; a flat top, and a sliding lid or cover closing the opening in the top and provided with a handle; laterally-extending guide-rails on the top 25 projecting beyond the body for the cover to slide on; handles on the sides of the body, and legs under the body at front and back, supporting the bottom clear of the floor. The interior space or horseshoe shape is lined with 30 fire-brick. The grate-surface is formed of separate grate-bars, each having in the front end an aperture of rectangular shape. In the flat front plate of the body is an opening situated above the horizontal center line and 35 closed by a hinged door, and below this opening is a horizontal shelf extending across the

front plate. Below the last-mentioned opening is the fuel-opening, provided with hinged doors, and below such opening the ash-pit opening with a hinged door.

40 The guide-rails for the sliding lid or cover upon the furnace-top, on opposite sides of the opening, extend beyond the body at one side a distance about equal to the width of the cover.

45 In the accompanying drawings, A indicates the body, of horseshoe shape; A', the flat front plate; B, the flat top, and C the sliding lid or cover.

D is the door of the upper opening for introducing the muffle. E is the shelf below it.

F is the fire-opening, and F' the doors that close it.

50 G G are the separate removable grate-bars, and g the aperture in the front end of each bar.

H is the ash-pit door.

55 I I are the handles on the sides of the body, K K, the legs beneath the bottom, and L L the laterally-projecting guide-rails for the sliding lid or cover.

Having thus fully described my invention, what I claim as new, and desire to secure by Letters Patent, is—

60 The design for a portable assay-furnace, substantially as herein shown and described.

65 In testimony that I claim the foregoing I have hereunto set my hand and seal.

JOHN G. ILS. [L. S.]
